CLAIM

The ornamental design for the skin massage roller, as shown and described.

DESCRIPTION

FIG. 1 is a perspective view of a skin massage roller according to a first embodiment showing my new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a perspective view of a skin massage roller according to a second embodiment showing my new design; FIG. 9 is a front view thereof; FIG. 10 is a rear view thereof; FIG. 11 is a left side view thereof; FIG. 12 is a right side view thereof; FIG. 13 is a top view thereof; and, FIG. 14 is a bottom plan view thereof.

The broken lines shown on the drawings depict portions of the skin massage roller that form no part of the claimed design.
